DESIGN FOR A DRAFT-LUG AND DRAW-BAR FOLLOWER.

SPECIFICATION forming part of Design No. 26,586, dated February 2, 1897.

Application filed December 21, 1896. Serial No. 617,274. Term of patent 14 years.

To all whom it may concern:

Be it known that I, ANDREW G. STEINBRENNER, a citizen of the United States, residing at the city of St. Louis, State of Missouri, have invented a certain new and original Design for a Draft-Lug and Draw-Bar Follower, of which the following is a full, clear, and exact description, reference being had to the accompanying drawings, forming a part of this specification, wherein—

This invention relates to a new and original design for a draft-lug and draw-bar follower; and it consists in the shape and configuration illustrated in the drawings and hereinafter fully described.

In the drawings, A indicates the front wall, which is ornamented by an opening a.

B indicates the side walls, which are formed with vertically-disposed projections or ribs b at their forward ends, the front faces of the projections being on a plane with the face of the front wall A, while the side walls, behind the projections, are formed with openings or perforations b'. The ribs b extend down to the bottom wall, but do not extend the full height of the side walls, they terminating short of the top wall. 25

C and D indicate the top and bottom walls, respectively, which are cut away from the rear, as shown. 30

The rear end is open.

What I claim is—

The design for a draft-lug and draw-bar follower, substantially as herein shown and described. 35

In testimony whereof I hereunto affix my signature, in presence of two witnesses, this 40 14th day of December, 1896.
